PACKING CASES INTENDED FOR TRANSPORTING FLAT GLASS

Stanley Swain, St. Helens, and Arthur Eden, Liverpool, England, assignors to Pilkington Brothers Limited, Liverpool, England, a corporation of Great Britain

Application June 10, 1953, Serial No. 360,738

Claims priority, application Great Britain
September 23, 1952

5 Claims. (Cl. 206—62)

This invention relates to improvements in or relating to packing cases intended for transporting flat glass.

Heretofore a case for the packaging of flat glass has been constructed on a U frame which comprises the bottom and end walls of the case, and to this U frame boards are nailed constituting the sides of the case, a lid being secured to the end walls and sides by nailing.

Long experience of handling such cases has indicated the necessity of continued vigilance in seeing that the case is not overturned on its side. If this happens, it causes more or less breakage of the sheets of glass in the case.

The cases also have the disadvantage of being heavy and consequently have a considerable bearing on freight charges.

A main object of the present invention is to provide a packing case for flat glass which can be handled quite easily by unskilled labor without damage to the contained commodity, and to provide a case in which the glass becomes readily available without destroying the case so that the latter may be used for storing glass after some has been removed from the case, and a further main object is to construct a case having the advantages above mentioned which shall be light compared with the well-known wooden cases.

The present invention comprehends a novel principle of structure for cases intended for packaging flat glass characterized by the combination of cavity walls with the U frames forming the narrow bottom and narrow end walls of the case.

A packing case for flat glass constructed in accordance with the present invention comprises cavity wall units each constituted by the mounting of panels on each side of a peripheral frame which separate the panels at such a distance apart that the panels cannot touch by flexing, the peripheral frame being secured to the elements of the U frame.

The means securing the panels to the peripheral frame are preferably also employed to secure the cavity wall assemblies to the U frame.

Accordingly if the inner panel was not present the peripheral frame would register with the elements of the U frame.

With such form of construction ordinary blows on the outer panel are taken up by the outer panel flexing or distributing the effect to the peripheral frame and if the force strikes the area of the panel overlapping the peripheral frame the latter passes the stresses through the U frame, thus leaving the glass unharmed.

The panels may be formed of resin impregnated sheet material, solid fibre board or thin wood but preferably are formed for sake of lightness combined with strength coupled with the capacity to flex, of corrugated fibre board.

A preferred form of packing case for flat glass constructed according to the present invention is characterised by the inner panel of both cavity wall units being constituted of corrugated fibre board and the outer panel

2

of one of the cavity wall units including an articulation parallel to the lid and bottom of the case.

By corrugated fibre board is meant that well-known industrial commodity which consists of a corrugated sheet of cardboard secured by adhesive between two flat sheets of cardboard. The grade and strength of the fibre board will be chosen according to the load which the packing case is intended to carry.

The outer panels of the cavity wall units may be made of solid fibre board, resin impregnated sheet material or of thin wood. The top of the panel, which is provided with the articulation, may be separate from the rest of the panel, but hingedly connected thereto for example by a flexible element so that the top part can be hinged relatively to the part below the articulation, thus the paneling including the articulation can be readily opened back and then the inner panel, being formed of corrugated fibre board, is sufficiently resilient to permit it being bent away from the glass in order to give access to the nearest sheet of glass.

The articulated outer panel may be formed by constructing the outer panel of one continuous sheet of suitable material and weakening the sheet to form the articulation in the panel.

Alternatively, the articulated panel may be formed of corrugated fibre board and the outer ply thereof scored to form the articulation.

Each cavity wall unit may be constructed on a rectangular frame in which each end element of the frame is overlapped at each end by the top and bottom elements of the frame, the inner and outer panel elements being secured to each side of the frame, the inner panel on the one side wall unit of the case being scored at the level of the inner face of the bottom of the U frame and bent at right angles at the score line and extended beyond the score line to cover the bottom of the U frame, and the outer panel of the other side wall unit having a score line near the top so that the top of the outer panel can be hinged back as a flap thereto to facilitate access to the glass.

In order that the invention may be more clearly understood, a preferred form of embodiment thereof in a packing case will now be described by way of example with reference to the accompanying drawing which depicts approximately to scale a case constructed to contain 50 square feet of sheet glass.

In the drawings, Fig. 1 is a perspective exploded view illustrating the construction of the members of the packing case; and

Fig. 2 is a perspective of the assembled and closed packing case.

In the construction illustrated the U-shaped frame of the packing case of rigid construction is made of wood of about $\frac{3}{4}$ inch thick and comprises a bottom 1 for the case and two end walls 2 secured to the bottom by nailing each end wall, having a batten 3 secured thereto near the top and bottom, for example by nailing, said battens overlapping the end walls 2 to an extent to accommodate between the overlaps the cavity side walls of the case, so that the ends of the battens lie flush with the outer faces of the cavity wall units.

The cavity wall units each comprise a rectangular frame including end elements 4, and top and bottom elements 5, the top and bottom elements overlying the contiguous ends of the side elements 4. The cavity wall units at each side of the case are completed by attaching to the rectangular frame inner and outer panels 6, 7 which are secured to their respective frames.

On the one side of the U shaped frame the outer panel of the cavity wall unit is nailed to all four elements of the wall frame, and the inner panel 6 is secured to the top element 5 and the side elements 4 of the frame by the

nails which secure the outer panel thereto. The inner panel, however, is of greater length than the inner face to the case by the width of the bottom 1 of the U shaped frame. The inner panel 6 is scored along a line indicated at 8 so that the extension 9 can be folded at right angles of the inner panel and completely overlie the bottom of the U shaped frame.

The other cavity wall unit is constituted by an inner panel 6 which is nailed to the two side elements 4 and the bottom element 5 of the respective panel frame, but is not secured to the top element 5, whilst the outer panel 7 is scored along the line indicated at 10 so that the outer panel is articulated at the score line and can be swung outwardly as a flap to the part below the score line as is clearly shown in the drawing.

The outer panel is secured to the bottom and side wall elements by nailing, and the nailing is used to secure the inner panel to the panel framing, but the upper part of the outer panel 7, that is the part above the score line 10, is free of the side elements 4, but is secured, for example by staples, to the top element 5, which therefore is movable with the flap portion about the score line.

The two panels constituted as herein described, are nailed to the U frame by the nails securing the panels to the panel frame. When the panels are secured in position against the U frame and flat glass is packed tightly therein, the lid 11 is nailed on.

The one receiving the case of glass can readily remove the lid without spoiling the case, and the upper part of the panel having the score line 10 can then be tilted back as shown in the drawing, and the inner wall can be bent back as diagrammatically illustrated in a somewhat exaggerated manner by the chain line 12, giving easy access to the nearest sheet of glass, and if only one or two sheets have to be removed, the outer panel can be placed back in upright position, and the lid reapplied to again complete the packing case.

Experiments have shown that a packed packing case constructed according to the invention can be roughly handled, even to the extent of being thrown over on to its side, without damage to the glass, which effect is astonishing to those used to packing flat glass for transport.

A packing case constructed according to the invention is easily assembled, can be manipulated by unskilled labor, and is light compared to the well-known wooden packing cases, so that not only is there a great saving in loss by damage to the owners of the glass, but less cost is involved in the transport of the glass, whilst the accessibility of the glass afforded by the flexible inner panels of the cavity walls avoids damage to the crate or damage to the glass in gaining access thereto.

We claim:

1. A relatively flat and narrow packing case for packing flat glass, comprising a U-frame constituting a narrow bottom and narrow end walls to the said case, side wall units having a surface area substantially larger than said end wall units, said side walls each comprising a pair of inner and outer panels and a peripheral frame secured to said U-frame and separating said inner and outer panels one from the other, said peripheral frame being of such thickness that the panels of each pair are incapable of touching each other by flexing, and a lid for closing the said case, the outer panel of one side wall unit including a flap articulated about a score line near the top thereof parallel to the said lid and the said bottom.

2. A relatively flat and narrow packing case for packing flat glass, comprising a U-frame constituting a narrow bottom and narrow end walls to the said case, side wall units having a surface area substantially larger than said end wall units, said side walls each comprising a pair of inner and outer panels and a peripheral frame secured to said U-frame and separating said inner and outer panels one from the other, said peripheral frame being of such

thickness that the panels of each pair are incapable of touching each other by flexing, the inner panel of at least one side wall unit comprising corrugated fibre board and being extended in length and folded back substantially at right angles to overlie the said bottom, and a lid for closing the said case, the outer panel of at least one side wall unit being composed of corrugated fibre board and including a flap articulated about a score line near the top thereof parallel to the said lid and the said bottom.

3. A relatively flat and narrow packing case for packing flat glass, comprising a rigid U-frame having narrow bottom and narrow end walls and open on opposite sides, each of said walls constituting a rigid board arranged so that their edges face the sides of said frame, said U-frame serving as a receptacle to receive therein flat glass extending transverse to the planes of said boards, two side wall units closing the open sides of said U-frame, and secured thereto against the edges of said U-frame, each of said side wall units having a surface area substantially larger than that of either of said end walls, and comprising a pair of spaced inner and outer panels extending across the corresponding side of said U-frame, and a peripheral frame separating and secured to said inner and outer panels, said peripheral frame being of such thickness that the panels of each pair of panels are incapable of touching each other by flexing, whereby any stress on the outer panel is transmitted to the peripheral frame and from said peripheral frame to said U-frame edgewise thereof, and a lid for closing the case.

4. A relatively flat and narrow packing case for packing flat glass as described in claim 3, wherein battens are secured to said end walls and extend outwardly beyond the edges of said end walls and across the ends of said wall units to confine said wall units in position against the edges of said U-frame.

5. In combination, a relatively flat and narrow packing case, comprising a rigid U-frame having narrow bottom and narrow end walls and open on opposite sides, each of said walls constituting a rigid board arranged so that their edges face the sides of said frame, said U-frame serving as a receptacle for flat glass, two side wall units closing the open sides of said U-frame, and secured thereto against the edges of said U-frame, each of said side wall units having a surface area substantially larger than that of either of said end walls, and comprising a pair of spaced inner and outer panels extending across the corresponding side of said U-frame, and a peripheral frame separating and secured to said inner and outer panels, said peripheral frame being of such thickness that the panels of each pair of panels are incapable of touching each other by flexing, whereby any stress on the outer panel is transmitted to the peripheral frame and from said peripheral frame to said U-frame edgewise thereof, and a lid closing the case, and flat glass in said case confined in the U-frame between said side wall units and extending transverse to the planes of said boards, whereby said flat glass is protectively packaged in said case.
